[57] CLAIM

The ornamental design for a combination telephone set and answering machine, as shown.

DESCRIPTION

FIG. 1 is a left side, top and front perspective view of a combination telephone set and answering machine showing my new design in cradled relationship;

FIG. 2 is a top plan view thereof;

FIG. 3 is a front elevational view thereof;

FIGS. 4 and 5 are respectively right and left elevational views thereof;

FIG. 6 is a rear elevational view thereof; and

FIG. 7 is a bottom plan view thereof.

The broken line showing of a transparent surface at the lower right area of the stand in FIGS. 1-3 is for illustrative purposes only and forms no part of the claimed design.
